CLAIM

The ornamental design for a headband for over ear hearing protector as shown and described.

DESCRIPTION

FIG. 1 is a perspective view of a headband for over ear hearing protector showing the new design;

FIG. 2 is a front view thereof;

FIG. 3 is a left-side view thereof;

FIG. 4 is a right-side view thereof;

FIG. 5 is a bottom view thereof;

FIG. 6 is a top view thereof; and,

FIG. 7 is a back view thereof.

The broken line depict portions of the headband for over ear hearing protector that form no part of the claimed design.

1 Claim, 5 Drawing Sheets
